UNITED STATES PATENT OFFICE.

FERDINAND HERBIN, OF AMESBURY, MASSACHUSETTS.

DESIGN FOR A CHUCK FOR HAT-BLOCKS.

SPECIFICATION forming part of Design No. 24,949, dated December 3, 1895.

Application filed October 29, 1895. Serial No. 567,323. Term of patent 8½ years.

To all whom it may concern:

Be it known that I, FERDINAND HERBIN, of Amesbury, in the county of Essex and State of Massachusetts, have invented and produced a new and original Design for a Chuck for Hat-Blocks, of which the following is a full, clear, and exact description.

Reference is to be had to the accompanying drawings, forming a part of this specification, in which similar characters of reference indicate corresponding parts in both the figures.

Figure 1 is a perspective view of a chuck for hat-blocks, the same embodying my new design; and Fig. 2 is a vertical sectional view thereof.

The leading feature of my design consists in the chuck, the plate *a* of which is of ap-

proximately circular contour with opposite peripheral recesses *a'*, the projection *b* of the chuck depending centrally, and a round opening *b'* appearing, ranging vertically through the plate and projection.

Other features are the thickened side portions *c*, having beveled inner sides *c'*, and the openings *d*, appearing in the depressed central part of the plate *a*.

I claim—

The design for a chuck for hat blocks, herein shown and described.

FERDINAND HERBIN.
